UNITED STATES PATENT OFFICE

EDWIN F. ROWSE AND HARRY E. JOHNS, OF HOMESTEAD, PENNSYLVANIA.

DESIGN FOR AN IRONING-BOARD.

SPECIFICATION forming part of Design No. 28,612, dated May 10, 1898.

Application filed September 17, 1896. Serial No. 606,186. Term of patent 7 years.

To all whom it may concern:

Be it known that we, EDWIN F. ROWSE and HARRY E. JOHNS, citizens of the United States, residing at Homestead, in the county of Allegheny and State of Pennsylvania, have invented and produced a new and original Design for an Ironing-Board, of which the following is a specification, reference being had to the accompanying drawing, illustrating the same, in which the figure is a perspective view illustrating our novel design for ironing-boards.

This invention has relation to a certain new and original design for ironing-boards; and it consists in the novel configuration of parts, as hereinafter described, and illustrated in the accompanying drawing.

With reference to the drawing, *c* designates the base portion of the ironing-board, which

is oblong in shape with rounded ends and upper edge beveled; *b*, the cylindrical pillar, having a circumferential groove *b'* near its lower end, and *a* the arm or board proper, tapered from one end to the other and provided with rounded ends and beveled upper edge, the parts being of the particular configuration shown and described and assembled to present an ironing-board of the design illustrated in the drawing forming part hereof.

What we claim is—

The design for an ironing-board as herein shown and described.

EDWIN F. ROWSE,
HARRY E. JOHNS.
